UNITED STATES PATENT OFFICE.

EDWARD A. DORMAN, OF NEW YORK, N. Y., ASSIGNOR TO JOHN H. DORMAN, OF NEW YORK, N. Y.

JACK.

1,367,307.

Specification of Letters Patent. Patented Feb. 1, 1921.

Application filed May 27, 1919. Serial No. 300,162.

To all whom it may concern:

Be it known that I, EDWARD A. DORMAN, a citizen of the United States, and a resident of New York city, in the county of 5 New York and State of New York, have invented certain new and useful Improvements in Jacks, of which the following is a specification.

The invention relates in general to a lifting jack of the type designed to constitute 10 an automobile accessory and which is usually provided with a horizontally extending actuating lever for actuating the lifting mechanism and further the invention relates 15 to that type of lifting jacks in which the manipulation of a reverse controlling mechanism permit the use of the same mechanism for effecting either the raising or lowering of the lifting element of the jack.

20 The primary object of the invention is to provide a simple form of jack designed to respond to the requirement for a light, compact and powerful jack which will develop unusual power and which can be positively 25 actuated in either its lifting or lowering movement and will function independently of any careless actuation on the part of the operator.

Broadly, this object is attained by 30 providing a control for the actuating mechanism in which the several operable parts are independently spring controlled so as to function independently of the movement of the actuating lever into its limiting position.

Another object of the invention is to provide a simple form of jack which will economically utilize the muscular effort imposed upon the actuating lever and transmit 40 the same through a system of compound levers to effect a powerful raising or lowering movement of the lifting element.

This object is attained broadly, first by 45 mounting the actuating lever in spaced relation to the lifting ratchet and causing said lever and the ratchet feeding pawl to constitute in effect a compound leverage designed to exert a powerful turning movement on the ratchet.

50 A still further object of the invention is to provide an organization of parts designed so that the movement of the lifting element into a limiting position will automatically disconnect the actuating lever 55 from the lifting element so that any con-

tinued movement of the actuating lever will not affect the position of the lifting element or deleteriously impose strains on the lifting mechanism.

Various other objects and advantages of 60 the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

Figure 1 is a view in side elevation of a preferred embodiment of the invention with the front of the casing removed and parts broken away to show internal construction and with the lifting mechanism in position 75 to raise the lifting element;

Fig. 2 is a view similar to Fig. 1 with the lifting mechanism in position to control the lowering movement of the lifting element and with the actuating lever in its fully 80 raised position;

Fig. 3 is a view similar to Fig. 2 with certain parts omitted and with the actuating lever in its fully lowered position;

Fig. 4 is a view similar to Fig. 1 with the 85 parts in advance of the ratchet removed and showing the lifting element locked in its fully raised position; and

Fig. 5 is a horizontal sectional view taken on the line 5—5 of Fig. 4 looking down 90 wardly as indicated by the arrow.

In the following description and in the claims, parts will be identified by specific names for convenience of expression but they are intended to be as generic in their application to similar parts as the art will permit.

In the drawings there is shown a standard 10 provided with a casing 11 in which is slidably mounted a lifting element in the 100 form of a rack bar 12 which carries the usual swivel head 13. A ratchet shaft 14 is mounted in the casing for free rotary movement about a horizontal axis and is provided with a pinion 15 constantly in mesh with 105 the teeth 16' of the rack bar 12. This shaft has a relatively large one-way ratchet 16 fixed to one end thereof. An actuating lever 17 is fulcrumed to the pin 18 carried by the casing and is positioned to the outside of 110

the ratchet and disposed vertically below the axis of rotation of the shaft 14. One arm of the lever extends exteriorly of the casing and constitutes a handle 19 by means 5 of which the device is actuated. The pin 18 constitutes a support for a retaining pawl 20, normally held in engagement with the teeth of the ratchet by a spring 21, and which acts to hold the ratchet from forward 10 rotation responsive to the load on the lifting element.

The other arm 22 of the lever 17 is relatively short, depends downwardly and extends slightly forwardly from the axis of 15 the pin 18 and has a relatively long up-standing feeding pawl 23 pivoted thereto for oscillation about a pivoting pin 24. A light-acting spring 25 normally acts upon the feeding pawl to hold the same in operative 20 engagement with the teeth of the ratchet as shown more particularly in Fig. 1.

In the normal operation of raising the load the ratchet wheel will be moved clockwise 25 by the downward movement of the lever acting through the feeding pawl and the retaining pawl will hold the ratchet from reverse movement responsive to the load during the dwell of the actuating lever 30 and during its upward or idle stroke.

Means are provided for controlling the lowering movement of the rack 12 under the influence of the load and for this purpose a latch 26 is operatively associated with 35 the feeding pawl and retaining pawl to successively withdraw the same from the path of movement of the ratchet teeth in timed sequence to the movement of the actuating lever 17. The latch 26 is substantially 40 U-shaped with its upper end pivoted to a pin 27 carried by the casing and, when free, is caused to swing anti-clockwise under the tension of a coiled spring 28 acting thereon to swing the lower end 29 toward the 45 two pawls. It is understood that the spring 28 is stronger than either of the springs 21 or 25. The upper side of the end 29 is provided with a pair of recessed cam faces 30 and 31 each designed to engage a pin 32 extending laterally from a position in the feeding pawl adjacent its ratchet engaging point 33. Similarly the lower side of the 50 end 29 is provided with a cam face 34 designed in the actuation of the device to engage a pin 35 on the retaining pawl to move the same into an inoperative position.

For the purpose of holding the latch in an operative position so as to permit the feeding and retaining pawls to function normally to lift the rack 12, there is provided a lifting and locking device in the form of a lever 36 having one end 37 extending exteriorly of the casing and constituting a handle for shifting the device. The inner

end of the lever is provided with a notch 65 38 designed to engage under a pin 39 carried by the latch and so arranged that the shifting of the latch into the position shown in Fig. 1 will raise the latch 26 into the inoperative position spaced from the pins 32 and 35 as shown in Fig. 1.

For the purpose of moving the feeding pawl into its inoperative position when the rack 12 has reached the limit of its upward movement, the lower end of the rack 75 is provided with a pin 40 extending laterally therefrom and designed to engage the under side of an inturned finger 41 constituting an extension from the upper end of a locking cam 42. This cam is fulcrumed 80 on a pin 43 and is provided on one side with a cam face 44 designed to engage the pin 32 to swing the feeding pawl 23 from the operative position shown in Fig. 1 into a position with the point 33 in spaced relation to 85 the teeth of the ratchet. A spring 45 normally acts on the cam 42 to hold the face 44 thereof in spaced relation to the pin 32 so as not to affect the feeding pawl except when the pin 40 is in engagement with the 90 locking cam 42.

In operation and with the parts in the position shown in Fig. 1 it will be understood that with each lowering movement of the actuating lever 17, the manual force 95 exerted on the outer end of the lever will act through the small power arm between the axis of rotation of the pins 18 and 24. This long work arm and short power arm thus formed reduce the length of resulting 100 movement and thus correspondingly increasing the resultant force. This short length but powerful force acts upwardly through the feeding pawl to advance the ratchet over a short rotary arch, as is well known in devices of this character. In this connection the device features the square fit of the point 33 against the engaged face of the ratchet during the entire swing of the pawl. It is appreciated that any ratchet feeding movement of the actuating lever will have no effect upon the retaining pawl, as this retaining pawl is pivoted concentrically with the axis of oscillation of the lever. This retaining pawl under these conditions will 110 act to hold the ratchet against reverse movement as is usual in such constructions and the fulcrum pin thus acts to provide a support for the retaining pawl.

Assuming that there is a load acting on 120 the rack 12 and that it is desired to gradually lower the load under control of the operator. The handle 37 is raised from the position shown in Fig. 1 into the positions shown in Figs. 2 and 3, thus removing the 125 locking device from the latch and permitting the powerful spring 28 to act on the latch and swing the same forwardly into

the position shown in either Figs. 2 or 3 depending upon the position of the actuating lever. Assuming first, that the lever is in the raised position shown in Fig. 2, it will be noted that the latch has swung forward until the cam depression 30 is in engagement with the pin 32. The latch acts under the force of the spring 28 to move the feeding pawl positively into spaced relation to the ratchet teeth. In this position, however, the cam face 34 is in spaced relation to the pin 35 thus permitting the retaining pawl to remain in its holding engagement with the ratchet. As the actuating lever is lowered from the position shown in Fig. 2 toward the position shown in Fig. 3, the cam face 34 is caused to engage the pin 35 and remove the retaining pawl from its holding engagement with the ratchet as shown in Fig. 3. The lowering of the actuating lever will at the same time raise the feeding pawl and its spring 25 will act thereon to swing the pin 32 from the recess 30 into the upper recess 31 and the point 33 will be thus raised into engagement with the ratchet teeth but in spaced relation to the flat face 46 of the next succeeding ratchet tooth in advance of the point. This will allow the weight to react through the pinion 15 and move the ratchet a distance less than the length of one radial tooth distance, thus permitting the lowering of the rack for a corresponding distance. This lowering movement is accordingly under control of the operator as he lowers the actuating lever and the powerful leverage effect of the device herein disclosed is utilized to ease the fall of the weight even over this small distance. The cam surfaces are so designed that as the actuating lever is again moved toward the raised position shown in Fig. 2, the retaining pawl is promptly released and positioned by its spring into holding engagement with the ratchet prior to the withdrawal of the feeding pawl into the inoperative position shown in Fig. 2.

As the lifting rack approaches the limit of its movement the pin 40 lifts the latch 42 and causes the cam face 44 to engage the pin 32 and thus moves the feeding pawl into an inoperative position and the rack 12 is thus locked against any further upward movement and against any accidental lowering movement which might be caused by the weight imposed thereon.

By means of a device of this character it is appreciated that the latch is at all times, except when locked in the position shown in Fig. 1, under the action of its own spring 28 which has a tendency to engage the feeding pawl and is not dependent for its action upon the movement of the lever into a limiting position or into engagement with the latch. The device will function even though the actuating lever is not moved

into its limiting position and will function even in the hands of a careless operator. If the operator does not manipulate a stroke of sufficient length the actuating mechanism will simply remain idle until a stroke of a length sufficient to actuate the pawl is effected. The number of movable parts have been reduced to a minimum but an effective leverage movement has been attained with the usual multiplicity of moving parts.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device of the class described, the combination with a lifting element, of an operating mechanism for lifting said element, said mechanism including an actuating ratchet, an operating lever, a feeding pawl actuated by the lever to feed the ratchet in its element lifting direction and means controlled by the movement of the element into its fully-lifted position and movable into engagement with said pawl to move the same into an inoperative position, said means including a member supported independently of both the lifting element and the pawl.

2. In a lifting jack, the combination of a lifting element, an actuating mechanism for moving the element toward a limiting position and means controlled by the movement of said element into its limiting position for automatically disconnecting the mechanism and element including an element supported independently of both the lifting element and the pawl.

3. In a lifting jack, the combination of a base member, a lifting element, an actuating mechanism for moving the element toward a limiting position and means controlled by the movement of said element into its limiting position for automatically disconnecting the mechanism and element, said means including a member mounted to swing about a fulcrum fixed with relation to the base member.

4. In a lifting jack, the combination of a lifting element, an actuating mechanism for moving the element toward a limiting position including a ratchet mounted for rotary movement and an operating pawl therefor and means controlled by the movement of said element into its limiting position for automatically disconnecting the mechanism and element.

5. In a lifting jack, the combination of a lifting element, an actuating mechanism for

moving the element toward a limiting position and means controlled by the movement of said element into its limiting position for automatically disconnecting the mechanism and element and means controlled by the initial movement of said element away from said limiting position for automatically restoring the operative connection between said element and said actuating mechanism.

6. In a lifting jack, the combination of a lifting element embodying a rack, a shaft provided with a pinion meshing with said rack and with a one-way ratchet, an operating lever fulcrumed in offset relation to the axis of rotation of the ratchet and provided with a feeding pawl adapted to engage the ratchet to positively operate the lifting element, a pendulous latch having an upper cam surface adapted to engage the feeding pawl, a spring for moving said latch into operative engagement with said pawl, said cam surface and said pawl being disposed in lapped relation whereby the operating lever will shift the pawl relative to the latch thereby to cause the pawl to alternately engage and disengage the ratchet and control the movement of the lifting element in the reverse direction and a cam engaged by said rack and in turn acting on said feeding pawl to move the same into an inoperative position.

7. In a lifting jack, the combination of a lifting element, actuating mechanism therefor including a ratchet wheel, an oscillating bell crank having a relatively short arm, fulcrumed vertically below the axis of the ratchet wheel, a lifting pawl carried by the free end of the short arm, a holding pawl pivoted on the lever fulcrum, and a pendulous latch pivoting at its upper end and with its lower free end normally positioned between the ratchet engaging ends of the two pawls, coacting surfaces on the pawls and the said free end, and a spring normally tending to bring said coacting surfaces into operative relationship and a member coacting with said latch to move said surfaces out of operative relationship.

8. In a lifting jack, the combination with a lifting mechanism including a vertically movable lifting bar and a power multiplying connection for actuating the bar, said mechanism including a one-way ratchet, a strain-receiving fulcrum pin positioned below the ratchet and in substantial vertical

alignment with the axis of rotation thereof, an actuating lever pivoted to said fulcrum pin, a relatively long upstanding feeding pawl pivoted to the lever close to the fulcrum pin for positively actuating the ratchet in a direction to act through the power multiplying connection to raise the bar, a relatively short retaining pawl pivotally mounted on said fulcrum pin to transmit the strains from the ratchet directly to the fixed fulcrum pin, said retaining pawl extending from the fulcrum in a direction substantially tangent to the path of movement of the teeth on the ratchet and engaging the teeth on the underside of the ratchet for preventing reverse movement of the ratchet when acted upon by the load on the lifting bar.

9. In a lifting jack, the combination with a lifting bar and mechanism for actuating the same, said mechanism including a one-way ratchet mounted for rotary movement about a horizontal axis, a fulcrum pin positioned vertically below said axis, an actuating lever pivoted to said pin and having a relatively short arm extending horizontally from the fulcrum pin, a relatively long actuating pawl pivoted to said short arm and extending upwardly normally to engage the ratchet teeth a short distance below a horizontal line passing through the axis of rotation of the ratchet whereby the pawl is raised bodily in a substantially vertical line tangent to the periphery of the ratchet as the pivoted lower end is rocked over a small angle on opposite sides of the vertical line through the axis of the ratchet and lever fulcrum.

10. In a lifting jack, the combination of a one-way ratchet, a load lifting member actuated thereby, a fulcrum pin mounted vertically below the axis of the ratchet, an actuating lever pivotally mounted on said pin, a relatively long feeding pawl having one end pivoted to the lever relatively close to its fulcrum, extending upwardly therefrom and provided with an engaging point for fitting against the teeth of the ratchet on one side thereof, said pawl having a substantially straight line upward movement during the actuation of the ratchet in the direction to raise the lifting member.

Signed at New York city, in the county of New York and State of New York this 15th day of May, A. D. 1919.

EDWARD A. DORMAN.
